(74) Attorney, Agent, or Firm — Coloplast Corp.,
Coloplast A/S; Nick Baumann(57) **CLAIM**

The ornamental design for a videoscope handle, as shown and described.

DESCRIPTION

FIG. 1 is a perspective view of a videoscope handle;
FIG. 2 is a front elevation view of the videoscope handle illustrated in FIG. 1;

FIG. 3 is a back elevation view of the videoscope handle illustrated in FIG. 1;

FIG. 4 is a left side elevation view of the videoscope handle illustrated in FIG. 1;

FIG. 5 is a right side elevation view of the videoscope handle illustrated in FIG. 1;

FIG. 6 is a top plan view of the videoscope handle illustrated in FIG. 1; and,

FIG. 7 is a bottom plan view of the videoscope handle illustrated in FIG. 1.

The broken lines form no part of the claimed design.

1 Claim, 6 Drawing Sheets(56)
